CLAIM

The ornamental design for a spoon rest with a hinged lid as shown and described.

DESCRIPTION

FIG. 1 is a top perspective view of the spoon rest with a hinged lid shown in an open position;

FIG. 2 is another top perspective view of the spoon rest with a hinged lid shown in a closed position;

FIG. 3 is a front, top perspective view of the spoon rest with a hinged lid thereof;

FIG. 4 is a rear, top perspective view of the spoon rest with a hinged lid thereof;

FIG. 5 is a front, bottom perspective view of the spoon rest with a hinged lid thereof;

FIG. 6 is a top view of the spoon rest with a hinged lid thereof;

FIG. 7 is a bottom view of the spoon rest with a hinged lid thereof;

FIG. 8 is a side view of the spoon rest with a hinged lid thereof;

FIG. 9 is a left side view of the spoon rest with a hinged lid thereof;

FIG. 10 is a rear view of the spoon rest with a hinged lid thereof; and,

FIG. 11 is a front view of the spoon rest with a hinged lid thereof.

The broken lines shown in the figures depict environmental subject matter that forms no part of the claimed design.
